UNITED STATES PATENT OFFICE

145,087

DESIGN FOR A DRILL PRESS STANDARD

Robert McFall Jones, Bellevue, Nebr., assignor to
Ralph Wilson Jones, Sr., St. Paul, Minn.

Application February 5, 1945, Serial No. 117,760

Term of patent 14 years

(Cl. D63—1)

To all whom it may concern:

Be it known that I, Robert McFall Jones, a citizen of the United States, residing at Bellevue, county of Sarpy, and State of Nebraska, have invented a new, original, and ornamental Design for a Drill Press Standard, of which the following is a specification, reference being had to the accompanying drawing, forming part thereof.

Figure 1 is a perspective view of a drill press standard showing my new design;

Figure 2 is a view similar to Figure 1 showing the standard bar in a lowered position; Figure 3 is a top plan view of the same; and Figure 4 is a side elevational view of the same. I claim:

The ornamental design for a drill press standard, as shown.

ROBERT McFALL JONES.
